UNITED STATES PATENT OFFICE

OSCAR E. BACKUS, OF MILWAUKEE, WISCONSIN

NOZZLE

Application filed November 14, 1929. Serial No. 407,162.

This invention relates to certain new and useful improvements in nozzles of the type illustrated in Patent No. 1,507,084, and has as one of its objects the provision of a nozzle in which the possibility of mechanically freezing its component parts is overcome.

Another object of this invention resides in the provision of a nozzle of the character described having two cooperating sections each provided with a straight bore adapted to be registered to form a continuous passage through the nozzle when the sections are in predetermined relative positions.

Another object of this invention resides in the provision of a simplified means for scattering or spreading the liquid as it issues from the nozzle.

And a further object of this invention is to simplify the construction of nozzles of the character described and thereby greatly facilitate their manufacture.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a view partly in elevation and partly in section of a nozzle embodying my invention, the cooperating sections being illustrated in their positions at which the nozzle is fully open;

Figure 2 is a view similar to Figure 1 illustrating the nozzle fully closed, and

Figure 3 is an end view of the nozzle taken on the plane of the line 3-3 of Figure 1.

Referring now more particularly to the accompanying drawing, the numerals 5 and 6 represent the body of the nozzle and the rotatable plug, respectively, from the outer end

of which the stream of liquid issues. The body 5 has its lower portion enlarged and internally threaded, as at 7, for attachment to a conventional hose coupling, not shown, and its main portion is taperingly bored, as at 8, to receive the correspondingly tapered inner end 9 of the plug 6. It is noted that the taper of the bore 8 and the plug end 9 which is received therein is comparatively great to preclude all possibility of mechanical freezing. A nut 10 threaded on the innermost end of the plug, outwardly of a lock washer 11 having a flatted portion engaging a flat face 12 of the plug, holds the plug against withdrawal from the body.

The outer surface of both the body and the plug 6 are preferably conical and form continuations of each other as clearly illustrated, and the medial portion of the plug is knurled, as at 13, to facilitate rotation thereof with respect to the body.

The body and the plug are provided with bores 14 and 15, respectively, which are disposed eccentrically and angularly to the axis of the nozzle and are arranged so that when the plug and body are in their relative positions illustrated in Figure 1, they form continuations of each other. In this condition the nozzle is fully open. The outermost end of the bore 15 in the plug terminates short of the nozzle end and communicates with a bore 16 of smaller diameter, a shoulder 17 being formed between the bores 15 and 16. The shoulder being formed by the end of the drill used to form the bore 15 is directed at an outward angle so that liquid flowing through the nozzle, in striking the shoulder, is deflected at an angle to give the spray a conical shape.

By turning the plug with respect to the body to restrict the passage afforded by the bores 14 and 15, the liquid in leaving the bore 14 strikes the conical wall 9 of the plug before entering the bore 15 and is thus given a spiral motion to issue from the nozzle as a revolving cone.

The restriction of the passage which turning of the plug affords breaks up the particles or drops of liquid so that an exceedingly fine spray is obtained, and when the plug is

turned to its position illustrated in Figure 1 in which the two bores 14 and 15 are aligned, a practically solid stream issues from the nozzle.

5 It is noted that by varying the length of the bore 16, or by changing its diameter to increase or decrease the shoulder 17, the shape of the spray can also be varied, for if the bore 16 is relatively long the effect of the shoulder 10 will be minimized and where the shoulder is increased in width by a reduction of the diameter of the bore 16 the effectiveness thereof is increased.

From the foregoing description taken in connection with the accompanying drawing, it will be readily apparent to those skilled in the art to which an invention of this character appertains that I provide a nozzle of extreme simplicity and design, having a 20 straight bore, in which the possibility of mechanical freezing of its cooperating elements is eliminated, and which is so constructed as to be easily manufactured.

What I claim as my invention is:

25 1. In a nozzle of the character described, a member having a tapered bore axial to the longitudinal axis of the nozzle as a whole, a second member having a correspondingly tapered portion receivable in said bore to be 30 rotatable with respect to the first-mentioned member about said axis of the nozzle, each of said members having straight bores eccentric to the axis of the nozzle and adapted to be aligned when the members are in a 35 predetermined relative position, and the second member having means for spreading liquid issuing therefrom.

2. In a nozzle of the character described, 40 two cooperating members rotatable with respect to each other about the longitudinal axis of the nozzle as a whole, each of said members having a bore disposed eccentrically and at an angle to said longitudinal axis, and the connection between the members being 45 such that when the members are rotated to partially disalign the bores liquid passing therethrough is given a whirling motion.

3. A nozzle of the character described, 50 comprising a body member having a tapered bore axial to the longitudinal axis of the nozzle as a whole, a plug having a correspondingly tapered portion received in said bore whereby the plug is rotatable with respect to the body member about said axis of 55 the nozzle, and the body member and plug having straight eccentric bores disposed at an angle to the longitudinal axis of the nozzle adapted to be aligned and disaligned upon rotation of the plug in the body member, and 60 means formed in the bore of the plug for causing fluid passing through the nozzle to spread as it leaves the nozzle.

4. A nozzle comprising two cooperating 65 members rotatable with respect to each other about the longitudinal axis of the nozzle as

a whole, and said members having straight bores adapted to be axially aligned to form an unrestricted passage through the nozzle when the members are in predetermined relative positions, the axes of the bores being at an angle to the longitudinal axis of the nozzle whereby the area of the passage is variable by relative rotation of the members, and the juncture of the members at the meeting ends of the bores being near the ingress end of the nozzle so that the bores cooperate to impart a spiral motion to the fluid passing therethrough.

5. A nozzle comprising two cooperating members joined for relative rotation about the longitudinal axis of the nozzle as a whole with the juncture of the meeting central portions of the members near the ingress end of the nozzle, each of said members having a straight bore with one end opening eccentrically to said meeting central portion of its member, so that upon relative rotation of the members, the meeting ends of the bores may be offset with respect to each other to increase and decrease the degree of communication therebetween and to impart a spiral motion to liquid flowing therethrough.

6. A nozzle comprising two members which together form a structure symmetrical about an axis common to both members, means rotatably connecting the members for relative rotation about said axis with their point of juncture substantially intermediate the ends of the nozzle and the outer surfaces of the members substantially continuous with each other, each of said members having a straight eccentric bore at an angle to said axis whereby the bores may be off-set with respect to each other by relative rotation of the members to increase and decrease the degree of communication therebetween and to impart a spiral motion to fluid flowing therethrough, and a shoulder at the discharge end of the outermost bore to spread the fluid as it issues from the nozzle.

In testimony whereof I have hereunto affixed my signature.

OSCAR E. BACKUS.
